UNITED STATES PATENT OFFICE.

GEORGE M. EATON, OF PITTSBURGH, PENNSYLVANIA, ASSIGNOR TO WESTINGHOUSE ELECTRIC & MANUFACTURING COMPANY, A CORPORATION OF PENNSYLVANIA.

COOLING SYSTEM FOR DYNAMO-ELECTRIC MACHINES.

1,365,309.

Specification of Letters Patent. Patented Jan. 11, 1921.

Application filed March 14, 1917. Serial No. 154,902.

To all whom it may concern:

Be it known that I, GEORGE M. EATON, a citizen of the United States, and a resident of Pittsburgh, in the county of Allegheny and State of Pennsylvania, have invented a new and useful Improvement in Cooling Systems for Dynamo-Electric Machines, of which the following is a specification.

My invention relates to ventilating apparatus, particularly of the type that is used in connection with dynamo-electric machines, and it has for its object to provide means for substantially eliminating foreign matter, such as snow and dirt, from the ventilating air that is delivered to such machines.

It is well known that the proper ventilation of electric driving motors and of auxiliary apparatus for railway vehicles is an important factor in the operation thereof and, as the electrical apparatus is usually placed beneath the floor of the vehicle, there is a great tendency for dust and moisture to enter into the ventilating system that may be employed in connection therewith. This tendency is particularly pronounced on electrified divisions of main-line railroads on which the high train speeds and open right-of-way result in the production of much dust and in particularly bad snow conditions. As the various forms of baffles and screens usually embodied in self ventilated apparatus have been found unsatisfactory, under the above described conditions, I propose to free the air of foreign matter before it is delivered to the machines by providing a combined ejector and centrifugal separating device in the intake passage to the blower.

In the accompanying drawings, Figure 1 is a plan view showing the arrangement of the electrical apparatus beneath the floor of a railway vehicle; Fig. 2 is a side elevation of the apparatus shown in Fig. 1, and Fig. 3 is an enlarged sectional view along the line III-III of Fig. 1, showing the details of my invention.

The outlines of the floor of a railway vehicle are shown by the broken lines in Fig. 1. A truck is pivotally related to the floor and electric motors 2 are suitably geared to the driving wheels 3 of the truck 1. A transformer 4, for supplying power to the motors 2, is suitably supported by the floor of the car and is located adjacent to the motors. An auxiliary motor 5 is coupled to a centrifugal blower 6 which is provided with an air intake passage 7, the details of which will be herein after described. The blower 6 is further provided with discharge passages 8 and 9 which deliver air to the motors 2 and to the casing 10 of the transformer 4, respectively. An auxiliary passage 11 is connected to the casing 10 of the transformer at a point where it receives a portion of the air that has passed through the transformer. It is to be understood that the transformer 4 and the motors 2 may be ventilated in series and that the auxiliary passage 11 may as well be connected at any point in the system, my object being to insure that heated air, at somewhat above atmospheric pressure, shall be delivered to the passage 11.

As best shown in Fig. 3, the intake passage 7 comprises a duct 12, the intake end of which is located at a point near the edge of the car floor and, preferably, considerably above the driving wheels 3. The duct 12 has a downwardly extending and gradually constricted portion 13 that terminates, at its lowest point, in an orifice 14. The passage 7 expands upwardly from the orifice 14 and then extends downwardly to the point where it is connected to the intake opening of the blower casing 15. The auxiliary passage 11 is secured to the intake passage 7 and is provided with a discharge opening 16 that is alongside, and merges with the orifice 14.

Having described the various parts entering into my invention, the operation is as follows:

The operation of the blower 6 causes air to be drawn into the duct 12 at a medium velocity which rapidly increases as the air passes into the constricted portion 13. The suction of the blower and the form of the passage 7 then cause the air to take a reverse turn above the orifice 14, but it will be readily understood that any particles having a specific gravity greater than that of the air will have a tendency to be expelled through the orifice 14 because of their inertia and of the centrifugal action of the air current as it makes the reverse turn. The above-described separation of foreign matter from the air is effective under most conditions of operation, but it is possible that, under certain atmospheric conditions and with the blower operating at full speed, there may be a tendency for air to be drawn into the passage 7 through the orifice 14. The possi-

bility of such a condition, however, is entirely avoided by the discharge of heated air, under pressure, through the auxiliary passage 11 and its discharge opening 16, the arrangement acting as an ejector to always insure that a certain amount of air, together with the foreign matter, shall be discharged through the orifice 14. The discharge of heated air through the auxiliary passage 11 10 performs another function in preventing the formation of ice in the orifice 14 whenever a large amount of snow enters the duct 12. The presence of the snow would otherwise tend to entirely or partially close the intake 15 passage 7 and render the ventilating system ineffective. As previously pointed out, the intake of the auxiliary passage 11 may be located at any point in the ventilating system and its position may be altered in accordance with variations in atmospheric 20 conditions. For example, heated air, at substantially atmospheric pressure, may be used during cold weather, while air at substantially outside temperature but at a pressure 25 considerably above that of the atmosphere may be used during warm weather.

While I have shown my invention in a simple and preferred form and as applied to an auxiliary blower, it is not so limited 30 but may be as readily applied to self-ventilated machines and is susceptible of various modifications within the scope of the appended claims.

I claim as my invention:

35 1. In a cooling system, the combination with a blower provided with an air intake passage, and a discharge passage, of means for continuously utilizing a portion of the air discharged by said blower to remove foreign matter from said intake passage.

40 2. In a cooling system, the combination with a blower provided with an air intake passage, and a discharge passage, of an ejector means located in said intake passage and continuously operated by a portion of the air discharged from said blower for removing foreign matter from the air delivered to said blower.

45 3. In a cooling system, the combination

with a blower provided with an air intake 50 passage and a discharge passage, of means for continuously utilizing the difference in pressure existing between the respective passages to remove foreign matter from the air delivered to said blower. 55

4. In a cooling system, the combination with a blower provided with an air intake passage and a discharge passage, of an air passageway between said passages so arranged that the passage of air therethrough 60 serves to eject foreign matter from the air delivered to said blower.

5. In a system of ventilation, the combination with a blower provided with an intake passage and a discharge passage adapted 65 to deliver cooling air to heat-generating apparatus, of means for utilizing a portion of the air delivered to said apparatus to prevent the formation of ice in the said intake passage. 70

6. In a cooling system, the combination with a blower provided with an intake passage and a discharge passage, and means whereby a portion of the air from said intake passage and a portion from said discharge passage are utilized to remove foreign matter from the air of said intake passage. 75

7. In a heat producing device, a cooling system consisting of a blower, an air intake 80 passage and a discharge passage, and means whereby a portion of the heated air from said discharge passage is brought into engagement with said intake passage to prevent the formation of ice therein. 85

8. In a heat generating apparatus, a cooling system consisting of a blower, an air intake passage provided with an orifice, and a discharge passage, and means whereby a portion of the heated air in said discharge 90 passage is utilized to heat said intake passage and to remove foreign matter from the air in the intake passage through said orifice.

In testimony whereof, I have hereunto subscribed my name this 28th day of Feb. 95 1917.

GEORGE M. EATON.
